MEANS FOR RECORDING SOUND

Original Filed Nov. 16, 1920

INVENTOR:

A. F. SYKES,
By his Attorneys,

Benjamin Wright

UNITED STATES PATENT OFFICE

ADRIAN FRANCIS SYKES, OF NEW BARNET, ENGLAND

MEANS FOR RECORDING SOUND

Original application filed November 16, 1920, Serial No. 424,421, and in Great Britain November 18, 1919.
 Divided and this application filed May 15, 1925. Serial No. 30,605.

This application is a division of my U. S. Patent No. 1,711,551, May 7, 1921.

This invention relates to apparatus for the conversion of sound into equivalent variation of electric currents or potentials and to the conversion of electric currents or derivatives thereof into mechanical vibration for the purpose of reproduction. My two prior Patents No. 1,711,551 and No. 1,639,713, describe means for effecting the first of these objects; 10 the present specification concerns means for reproduction.

The principles involved are very similar in both cases. I presume in the first place that true voice currents are required to be represented by the displacement of a plain mass, a term which is sufficiently explained in the above specifications. It consists in the present case of an acoustically inert coil carrying a sapphire. The sapphire engages with a wax surface of sufficient softness not materially to interfere with the vibrations which would be induced in the mass in the absence of the wax. By wax is meant the 20 usual composition employed in the production of master records.

The coil is simply floated on the wax surface for vertical or phonograph recording and suitable modifications are introduced to meet the needs of the lateral or gramophone cut. Such a coil when supplied with currents properly representing the voice, musical performance or telephone message, it is desired to record, does not vibrate in a manner truly corresponding to the electrical variations but on the contrary the wave form of the vibration of the coil differs from that of the electrical current passing through it in a very definite manner; neglecting the 30 resistance of the wax to penetration the harmonics are produced in value in the proportion of $1/f^2$ (where f is the frequency), that is, they are represented in a manner inversely proportional to the square of the frequency.

40 Hence in my invention the electric currents are in effect distorted artificially before they are supplied to the coil. The correct modification is that the harmonics are magnified in the proportion of the square of the frequency, 45 which change can be brought about by the

use of inductances in the following fashion:— Supposing the electrical variations available can supply no appreciable power they are in the first place magnified by a thermionic valve relay or the like, the last valve of which is fairly powerful. A small inductance is placed in the plate circuit of this latter valve and the variation of electrical potential on this inductance is the differential of the current in the plate circuit, so that every harmonic is exaggerated in proportion to its frequency. For this to be realized in practice the resistance of the plate circuit must be large compared with the impedance of the inductance used for the frequency considered. 55 The potential across the inductance is now caused to operate a second valve also with a small inductance in its plate circuit; the variation of potential on this second inductance is the differential of the plate current and hence every harmonic is exaggerated in the proportion of its frequency, so that the variations of potential on this second inductance referred to the original supply of current produced by the voice are exaggerated in the 60 proportion of the square of the frequency. 65

Again these variations are caused to operate a third valve designed to supply current to the recording coil. The term "coil" is to be understood in a broad sense; it may not involve a complete turn if a current transformer is used. A Fessenden vibrator might conceivably be adapted to the case.

Among resistances that may be encountered in apparatus for recording on wax may be 70 mentioned, firstly a thrust from the wax varying with and for small displacements proportional to the departure from the mean position; secondly a resistance of the nature of viscosity—a resistance depending upon the 75 velocity of the moving parts; thirdly the inertia of the recording element itself. Of these resistances which comply with the conditions requisite for a damped tone, the first only modifies in scale the true voice current 80 itself, the second can be corrected by an appropriate fraction of the differential of the voice current, the third by the second differential of the voice current. In the practice 85 of the invention, however, the inertia of the 90

engraving element constitutes so large a proportion of the total resistance that for most purposes it is not necessary to make any provision for any other resistances. Nevertheless if desired such compensation can be incorporated in the system.

Just as in the case of the detector the recording coil behaves as a plain mass and not as a resonator as is the diaphragm of a telephone or the like. A vibrating element of this character is never used in practical telephony or sound recording for two reasons. In the first place it is insensitive, and secondly it distorts the sound. By the use of relays of distortionless character now available the objection as to sensitiveness disappears; and by suitably modifying the wave form of the currents before allowing them to vibrate the coil the distortion is eliminated.

The point of view adopted is that in all cases the mass of the detecting or inscribing agency is compensated for completely regardless of the frequency; while elastic control or viscous damping are either, and preferably, made relatively negligible or are provided for by appropriate currents derived from the sound. Thus if the natural period of the engraving instrument corresponds to 250 vibrations a second, and should that be the only period which can be readily excited by the electrical forces brought to bear, at a frequency of 1000 vibrations a second the mass is largely the predominant factor and so determines the extent of the vibration and the electrical forces are artificially distorted to ensure that the mass will vibrate over the proper range notwithstanding that the frequency is much above the natural frequency of the instrument. The principle for dealing with any tone which occurs in the apparatus consists in reducing the electrical forces at the resonance point to the amount required to overcome the damping only.

Suppose a detector which derives current or potential from the sound equivalent to the excess pressure wave be available. Alternatively let a detector expressing the displacement wave be available and subject its potential to a process of differentiation so as to derive a result equivalent to the excess pressure wave. Let this detector control an amplifying valve in whose plate circuit is placed a large inductance in parallel with a combination of a small inductance, a condenser and a resistance all in series and so proportioned as to be the electrical equivalent of the mechanical vibrating system. By this I mean that the time period is the same and the damping of the same degree. The impedance of the electrical system must be sufficiently small as to permit the changes in valve current to be driven through without sensible modification. With this state of affairs the potential across the combination is such as to compensate for the mass, elasticity

and damping of the mechanical system for any frequency up to that when the impedance of the electrical combination becomes comparable with the resistance of the valve itself. In relation to the excess pressure wave of the sound the potential across the condenser, the resistance and the inductance respectively, is the equivalent of the unaltered wave, the first differential and the second differential respectively.

The velocity attained by the mechanical system at any instant is the mechanical equivalent of the plate circuit current and hence the amplitude developed is the integral of that current with respect to time and therefore corresponds to the displacement curve of the sound. At the resonant frequency the voltage across the condenser is equal and opposite to the voltage across the inductance and therefore the only potential supplied to the grid of the next valve is the potential across the resistance which is adjusted to compensate for the damping of the mechanical system. Additional damping could be provided by means of a supplementary coil attached to the main coil and more or less shortcircuited.

The reason for paying attention to the case of a system with one damped tone is because the usual vibrating device occurring in telephony comprises a magnet and armature together with a coil for varying the strength of the poles telephonically. For reasons of stability considerable elastic control must be provided, otherwise the armature simply flies to the pole or poles. By taking into account this control such a device could be operated on the lines of my invention. An example is furnished in the drawings which were filed with the present specification. Possibly by careful experimental study of a reed or diaphragm telephone receiver such an instrument could be improved as a recorder by compensating for each of its tones so as to render the resonant action more uniform.

The recording element most favoured at the present time is a small compact coil weighing about 5 grammes adapted for torsional vibration located in a single magnetic air gap (induction density about 15,000 c. g. s. lines) — that is, without iron armature. The coil is under weak elastic control purely for facilitating the use of a gravity method of determining the depth of cut in the wax. In place of the ordinary telephone currents providing a link between the detector and the recorder it is obvious that the detector may control directly or indirectly a high frequency transmitting set similar to any used for wireless telephony and so modulate a carrier wave but inasmuch as the modulated carrier is rectified before operating the recorder and therefore becomes a telephone current no description of such matters is included in this specification. In fact the recorder could register messages

or musical selections transmitted by wireless telephony from distant countries or from modulated carrier currents transmitted by means of wires. Apart from the subject matter of this invention, however, all such apparatus and schemes are dealt with in books on wireless telegraphy.

5 I now turn to the use in combination of the detector and the recorder. The standard of reference adopted has been the wave of excess pressure. Particle displacement as well as pressure difference over a small interval can be derived from the wave of excess pressure by a process of integration or differentiation as the case may be. The detector

10 described in United States Patent No. 1,639,713 takes the excess pressure as the standard. Although I have described apparatus using throughout the principle of the plain mass or non-resonant system cases may arise where the very great sensitiveness inherent in the combination of a microphone and sound concentrating trumpet presents great possibilities.

15 It has been observed that if the process is stopped at the stage when the mass is exposed on one side only to the wave of excess pressure and simply carries a coil immersed in a magnetic field, then the E. M. F. induced is in terms of particle displacement. British specification No. 160,223 shows such an apparatus

20 coupled to a recorder suitable for engraving particle displacement on a disk blank. Recordings intermediate between that of full excess pressure and particle displacement can be obtained by the use of an inductance in one

25 or other of the distortion circuits, which inductance tends more and more merely to check the current as the frequency rises and not to differentiate. These remarks are made because in making a record it may be necessary to take some account of the natural characteristics of the machine on which it is intended to reproduce it. My invention enables

30 the operator to compensate to various influences which would otherwise impair the fidelity of the reproduced sound.

35 Of course if the characteristic of the detecting or reproducing agency supplies one or more of the steps required by my system as described, then such step or steps would be omitted. In other words, if it is not desired

40 to record accurately the voice currents or potentials available but some modification thereof, the invention is varied accordingly; in fact in the making of a sound record the effect

45 obtained necessarily involves the combination of the detecting, engraving and reproducing instruments. In particular should the phonograph or gramophone tend to give undue prominence to a harmonic of a particular

50 pitch, such a harmonic could be taken account of in the recording by shunting one of the valve transformers with an oscillation circuit which at the particular frequency reduces the efficiency of transformation.

55 From the point of view of the deficiencies of a given sound reproducing machine or phonograph, the recording which in combination with the machine gives a faithful reproduction of the original sound may not it-

60 self represent anything very definite, which is really another way of saying that the art must remain experimental until standardized. Apart then from permitting an engraving to be made equivalent to, say, the displacement wave, that is, an engraving with a well understood meaning, the system provides scope for a wide range of tone control. Any derivative of the excess pressure wave either by integration or differentiation is theoretically obtainable and also intermediate stages.

65 Although I have described apparatus using throughout the principle of the plain mass or non-resonant system cases may arise where the very great sensitiveness inherent in the combination of a microphone and sound concentrating trumpet presents great possibilities.

70 By care and experiment such apparatus can be made to yield most useful results and in combination with a plain mass recorded as described such results can be engraved accurately on the wax.

75 Similarly it may happen that it is desirable to use the detecting part of the invention in conjunction with any recording telephone.

80 In the accompanying drawings, which illustrate the invention:—

85 Figure 1 illustrates the invention applied to recording on a disk.

90 Figure 2 is a plan of the engraving instrument shown in Figure 1.

95 Figure 3 is an enlarged detail view of the recording coil shown in Figure 1.

100 Figure 4 is a view of the same recording instrument applied to recording on a cylinder, and.

105 Figure 5 is a modified form of recording instrument.

110 Figure 1 is a diagram illustrating the principle of the invention as applied to a mechanical engraving system possessing as near as may be one tone. A detector, which may be of the kind described in my prior specification No. 705,713 (British No. 160223) with sensitive element controls the valve 42, in the plate circuit of which is placed an inductance 43, with iron core 53, and secondary winding 54, which transfers the potential variations with or without alteration of scale as circumstances allow to the valve 44, in the plate circuit of which is placed an inductance 45,

115 a resistance 55 and a condenser 56, all in series, and in parallel with the primary of a potential transformer 57 controlling the valve 46, which valve operates the coil 1 of the electromagnetic engraving instrument through the transformer 59. The engraving or recording instrument comprises a coil 1 capable of torsional vibration, that is, elastically pivoted on an axis 5 by means of the wire

120 69 of which the coil is wound, or if this is either too thick or too thin, by a separate wire. A cutting stylus 3 is attached to the coil. The wire 69 is knotted or otherwise enlarged at 70, so that the screwed ebonite

125 130

brushes 71, situated in the ebonite lever 65, pivoted at 66, can be used to tension the wire 69, and cause it to press tightly against the rubber pads 72, cemented to the lever 65. A counterbalancing adjustment is provided at 73. Figure 2 is a plan from above showing the engraving instrument in position between the poles 9, 10, of an electromagnet. Wires from the ends 70 of the coil lead to the mercury pools 74 and 75 into which the distorted currents are led by the conductors 76 and 77.

Figure 3 is a greatly enlarged transverse sectional view of the recording coil 1 for recording on the disk blank 28. It consists preferably of two coils 80 and 81 for providing the additional damping mentioned in an earlier part of the present specification. These coils are not in electrical connection and one of them is the main coil which receives the distorted currents. The other coil may be more or less shortcircuited. The coils are situated in the magnetic air gap between the poles 9 and 10 of a powerful electromagnet. The field strength would be about 15,000 c. g. s. units. To strengthen the coils, the turns of which are bonded together with shellac or other binding material, the central space is in part blocked in with wood or pitch 78. A central pin 79 carries the V shaped recording jewel 3. If the effective length of the winding is 400 cms and the maximum transformed current is 1 ampere, the force on the coil is approximately 300 grams on each side.

Figure 4 shows this same engraving device applied to a cylinder.

Figure 5 is another form of engraving device in which an instrument of the Bell receiver class is adapted to the case. The valve 46 operates the coil 58 of the electromagnetic engraving instrument through the transformer 59 and the leads 76 and 77. The engraving instrument comprises a permanent magnet 60 of the horse shoe type with laminated poles 61 and laminated armature 62 shaped so as to be as free as possible from tones likely to interfere with the recording and constrained by two wires 63, separated by the width of the armature and by the rubber pad 64, to which one end is cemented. The magnet is carried by the ebonite bracket 65 pivoted at 66 to a feed-screw carriage not shown and counter-balanced to secure the proper gravitational pressure on the stylus 3, shown engraving the disk 28. An adjustment block 67, elastically hinged at 68, permits the distance of the armature from the poles to be varied. It is to be understood that the wires 63 are stretched by the magnetic force and that the natural period is largely determined by these wires. For the system to be practicable it is necessary for it to have a frequency of the order of one thousand cycles a second though the best pitch is a matter for experiment and varies according to the proportions adopted. At this natural

frequency the electrical system, 45, 55 and 56, only allows the transformer 57 to supply the damping losses.

Conceivably if the armature were a diaphragm with N tones in an important acoustic region N systems in N valve transformers corresponding to 45, 55 and 56, or possibly in parallel could be incorporated in the scheme. Again if, as is preferred, in place of the magnet an armature and engraving device as in the previous figures of this specification be used the effect of undue resonance of the reproducing machine could be checked in like manner.

What I claim is:—

1. In means for recording sound, an electromagnetic recorder operating a stylus, which recorder has only a single period of vibration relative to its supporting structure, and valve circuits containing inductance, resistance and capacity, for modifying the effect of the natural period of the recording device.

2. In means for recording sound, an electromagnetic recorder operating a stylus, which recorder has only a single period of vibration relative to its supporting structure, and valve circuits for modifying the effect of the natural period of the recording device, such valve circuits containing inductance, resistance and capacity, the relation of the inductance and capacity being such that if forming a closed circuit such circuit would have substantially the same frequency as that of the recording device.

3. In means for recording sound, an electromagnetic recorder operating a stylus, which recorder has only a single period of vibration relative to its supporting structure, and valve circuits for modifying the effect of the natural period of the recording device, such valve circuits containing inductance, resistance and capacity in series with the plate circuits, the total impedance of the said modifying circuits being small compared with that of the plate circuits.

4. In means for recording sound, an electromagnetic recorder operating a stylus, which recorder has only a single period of vibration relative to its supporting structure, and an electric correcting means for modifying the effect of the natural period of the recording device, such recording device comprising the stylus, a conductor and damping means for the conductor.

5. In means for recording sound, an electromagnetic recorder operating a stylus, which recorder has one period of vibration relative to its supporting structure, and an electric correcting means for modifying the effect of the natural period of the recording device, such recording device comprising a stylus, a conductor and electromagnetic damping means for the conductor.

6. In means for recording sound, an electromagnetic recorder operating a stylus, which recorder has one period of vibration relative to its supporting structure, and an electric correcting means for modifying the effect of the natural period of the recording device, such recording device comprising a stylus, a conductor and an electromagnetic damping means for the conductor, which damping means consists of a coil carried by the conductor and admitting of any degree of shortcircuiting.

7. In means for recording sound, an electromagnetic recorder operating a stylus, which recorder has only a single period of vibration relative to its supporting structure, and an electric correcting means for modifying the effect of the natural period of the recording device, which correcting means shall include a device for integrating the lower tones electrically.

8. In means for recording sound, an electromagnetic recorder operating a stylus, said recorder having only a single period of vibration relative to its supporting structure, and valve circuits including impedance elements therein arranged to modify the effect of the natural period of the recording device.

In testimony that I claim the foregoing as my invention I have signed my name this first day of May, 1925.

ADRIAN FRANCIS SYKES.
